INVENTOR

Homer Ray Dill.

UNITED STATES PATENT OFFICE.

HOMER RAY DILL, OF IOWA CITY, IOWA.

DEVICE FOR HOLDING LABELS, DRAWINGS, AND PICTURES.

1,097,009.

Specification of Letters Patent. Patented May 19, 1914.

Application filed May 12, 1913. Serial No. 767,127.

To all whom it may concern:

Be it known that I, HOMER RAY DILL, a citizen of the United States, residing at Iowa City, in the county of Johnson and State of Iowa, have invented a new and useful Device for Holding Labels, Drawings, and Pictures, of which the following is a specification.

My invention relates to a device for holding labels, drawings, descriptive cards and pictures and the objects are, first, to hold labels, drawings, cards or pictures, such as are used in museums, stores and show-windows, at an angle so that they may be plainly seen and read; second, to prevent them from curling; and third to protect them from the dust and dirt. The holder is useful in the drafting-room and shops for holding and protecting a drawing while it is in use. I attain these objects by the device illustrated in the accompanying drawing, in which—

Figure 1 represents a perspective view of this improved device in position ready to receive a card and its protective covering. Fig. 2 is a transverse section thereof with a card in operative position therein.

In the embodiment illustrated —E— represents the frame of the holder supported by the foot —B—: these two parts being 30 preferably made of one piece of metal. A metal plate —D— is held in place by the turned edge, indicated at the break —C—, and the catch —A—. When a label is to be placed in the holder, the plate —D— is removed: a piece of celluloid, or other transparent material, the size of the plate, is placed in the frame, the label is now put in place and the plate —D— is inserted, all being held in place by —C— and —A—. To 40 remove the label press down on the catch —A—.

I claim:

A card support comprising a frame the upper member of which is substantially inverted U-shaped in cross section, a plate extending rearwardly from the lower frame member, and a forwardly extending spring tongue struck out of said plate adjacent said bottom frame member.

HOMER RAY DILL.
